(57) CLAIM

The ornamental design for a doll figure golf club cover as shown and described.

DESCRIPTION

FIG. 1 is a elevational view of a doll figure golf club cover showing my new design;

FIG. 2 is a left view thereof;

FIG. 3 is a right view thereof;

FIG. 4 is a rear view thereof;

FIG. 5 is a top view thereof;

FIG. 6 is a bottom view thereof;

FIG. 7 is a top-front-right elevational view thereof; and,

FIG. 8 is a bottom-left-rear elevational view thereof.

The broken lines in the drawings illustrate portions of the doll figure golf club cover which form no part of the claimed design.
